FOREIGN PATENT DOCUMENTS

WO 02064331 8/2002

Primary Examiner—Terry A. Wallace*(74) Attorney, Agent, or Firm*—Black Lowe & Graham, PLLC(57) **CLAIM**

I claim the ornamental design for the food chopper, as shown and described.

DESCRIPTION

FIG. 1 is a top view of the food chopper;

FIG. 2 is a left side view of the food chopper, the right side view being a mirror image;

FIG. 3 is a bottom view of the food chopper;

FIG. 4 is a front view of the food chopper;

FIG. 5 is a back view of the food chopper; and,

FIG. 6 is a perspective view of the food chopper.

The broken lines are for illustrative purposes only and form no part of the claimed design.
